(57) **CLAIM**

The ornamental design for a combined aerosol canister and cap, as shown and described.

DESCRIPTION

FIG. 1 is a front perspective view of my combined aerosol canister and cap

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken line is included for the purpose of illustrating a portion of the combined aerosol container and cap that together with the unshaded region forms no part of the claimed design.

1 Claim, 2 Drawing Sheets

FIG. 1**FIG. 2****FIG. 3**

FIG. 4**FIG. 5****FIG. 6****FIG. 7**
